United States Patent

Des. 239,681
Patented Apr. 27, 1976

239,681

COLLAPSIBLE MUSIC STAND

Donald R. Smith, Brookville, Ind., assignor to Manual Arts Furniture Company, Cincinnati, Ohio

Filed Nov. 15, 1974, Ser. No. 524,152

Term of patent 14 years

Int. Cl. D6—99

U.S. Cl. D6—18

FIG. 1 is a perspective view of a collapsible music stand embodying my design;

FIG. 2 is a side elevational view thereof, the opposite sides being the same;

FIG. 3 is a front elevational view thereof;

FIG. 4 is a rear elevational view thereof;

FIG. 5 is a top plan view thereof; and

FIG. 6 is a bottom plan view thereof.

I claim:

The ornamental design for a collapsible music stand, as shown and described.
